DIGITAL SWITCH

Hiroji Fujimoto, Kanagawa, Japan, assignor to Fujisoku Electric Co., Ltd., Kanagawa-ken, Japan

Filed Mar. 18, 1971, Ser. No. 125,925

Claims priority, application Japan Oct. 30, 1970

Term of patent 14 years

Int. Cl. D13—03

U.S. Cl. D26—13

FIG. 1 is a front perspective view of a digital switch showing my new design;

FIG. 2 is a rear elevational view thereof;

FIG. 3 is a plan view thereof;

FIG. 4 is a rear perspective view of another embodiment of the FIG. 1 switch wherein locking leaf springs for attaching the switch to a panel are provided on the opposite sides;

FIG. 5 is a left side elevational view of the FIG. 4 embodiment;

FIG. 6 is a bottom plan view thereof; and

FIG. 7 is a front elevational view thereof.

The broken lines are for illustrative purposes only.

I claim:

The ornamental design for a digital switch, as shown and described.
